DESIGN FOR A STEP FOR FLEXIBLE LADDERS

Harald Fritzner, Seattle, Wash.

Application May 27, 1944, Serial No. 113,770

Term of patent 14 years

(Cl. D15—8)

To all whom it may concern:

Be it known that I, Harald Fritzner, a citizen of Norway, residing at Seattle, Washington, in the county of King and State of Washington, have invented a new, original, and ornamental Design for a Step for Flexible Ladders, of which the following is a specification, reference being had to the accompanying drawing, forming a part thereof, in which:

Fig. 1 is a perspective view of a step for flexible ladders showing my new design;

Fig. 2 is a top plan view thereof; and

Fig. 3 is a fragmentary cross-sectional view taken along the line 3—3 of Fig. 2 in the direction of the arrows.

I claim:

The ornamental design for a step for flexible ladders, as shown.

HARALD FRITZNER.
